UNITED STATES PATENT OFFICE.

HENRY KLEIN AND PAUL J. KLEIN, OF DETROIT, MICHIGAN.

BUILDING CONSTRUCTION.

Application filed May 6, 1921. Serial No. 467,490.

To all whom it may concern:

Be it known that we, HENRY KLEIN and PAUL J. KLEIN, citizens of the United States of America, residing at Highland Park, Detroit, Michigan, have invented certain new and useful Improvements in Building Constructions, of which the following is a specification, reference being had therein to the accompanying drawings.

10 This invention relates to a building construction, in which a simple form of metallic reinforcement is used for the concrete walls of a house.

It has for an object the provision of a 15 form of reinforcement which may readily be assembled by unskilled labor.

A further object is to provide a form of reinforcement consisting of relatively inexpensive structural materials and in which 20 the reinforcing elements may be secured together in the simplest manner and with the least expenditure of time and energy.

With these and other objects in view, as will more fully appear in the specification, 25 the invention consists of features of construction, and the parts and combinations thereof or their equivalents as hereinafter described and set forth in the claims.

In the drawings,

30 Figure 1 is a front elevation of a building illustrating a preferred embodiment of the invention;

Fig. 2 is a horizontal section, a portion being a section of a lower story and another 35 portion a section of an upper story;

Fig. 3 is a vertical section through a wall adjacent to a pair of the reinforcing elements.

Fig. 4 is a perspective view of a fragment 40 of a wall showing the desired arrangement of the transverse flexible reinforcing elements;

Fig. 5 is a detail showing the manner in which the ends of the wire reinforcements 45 are secured in a perforation in the reinforcing plates;

Fig. 6 is a perspective view of the lower end of the reinforcing member used at a corner; and

50 Fig. 7 is a perspective view of the upper ends of a series of reinforcing plates illustrating the means by which they are held in position when first assembled.

The reinforcing framework illustrated in 55 the present embodiment of the invention consists of a series of vertically arranged flat

plates 1 preferably of a width substantially equal to the thickness of the wall before it receives the internal and external coats of stucco, plaster or other finish. These plates 60 are preferably bent to form a flange 2 at the bottom, anchoring means being provided at suitable intervals in the construction of the foundation wall to which the flanges are secured. The plates 1 have a series of holes 4 65 bored at intervals to receive reinforcing wires 5 preferably arranged diagonally as shown in Fig. 4. As a simple and convenient means for securing the wires to the plates, the ends of one or more wires are 70 passed through an opening 4 and a wedge member 6 which may conveniently be a cut nail driven into the hole with the ends of the wire to wedge them securely in place. It is preferred to arrange the reinforcing wires 75 in an inner series and an outer series spaced from the edge of the plates at a distance equal to approximately one-fourth of their width. Vertical reinforcing wires 7 may be secured to the diagonal wires at their intersection by means of short tie wires as illustrated in Fig. 4.

In setting up the plates 1 preparatory to setting the reinforcing wires 5 in place, it is convenient to use short lengths of pipe 8 85 passed through perforations 9 near the upper ends of the plates, these pipes being secured together by an ordinary coupling 10 and remaining in the finishing wall as an additional reinforcement.

90 Interior walls or partitions will have the same form of reinforcement but instead of using concrete, some lighter and cheaper plastic composition will be used, such as gypsum stucco, or magnesia-asbestos composition, or any other suitable or well known material of sufficient strength.

At corners, the reinforcing plates will 95 preferably be in the form of a cross of which the webs may be integral or formed as a composite beam such as shown at 12 in Fig. 6. Within the space constituting the extreme corner of the wall, a space through which the wires 5 do not extend, special reinforcing elements 13 are positioned, these 100 elements 13 consisting of vertical wires or rods secured in any suitable manner to one of the adjacent flanges and preferably extending outward at some distance from the flange. After this reinforcing framework 110 has been constructed, suitable molds will be set up on the inside and outside of each wall

and any suitable cement or concrete mixture will be poured between the molds and packed into the space between the plates 1 around the reinforcing wires 5.

5 The plates 1 may conveniently be of standard lengths connected end to end by plates 11 riveted to the abutting ends.

When the molds are removed, only the edges of the flat plates 1 will appear on the 10 surface of the wall and these edges will be entirely concealed by the application of an interior coat 14 of plaster or other suitable material and by an exterior coat 15 preferably of some ornamental stucco. As shown 15 in Figs. 1, 2 and 3, the wall of the second story is of less thickness than that of the first, the outer faces of the two sections being flush with each other and the shoulder formed by the lower section of the wall 20 extending inward farther than the upper section of the wall provides a seat for the ends of the joists 17 supporting the floors and ceilings.

As an additional securing means for the 25 joists, tie members 16 may be set in the cement at proper intervals when it is molded, these tie members preferably consisting of flat metallic straps suitably anchored in the concrete and adapted to be nailed or bolted 30 to the ends of the joists.

From the above description, it will be apparent that there is thus provided a device 35 of the character described possessing the particular features of advantage before enumerated as desirable, but which obviously is susceptible of modification in its form, proportion, details of construction and arrangement of parts without departure from the principle involved or sacrificing any of 40 its advantages.

While in order to comply with the statute the invention has been described in language more or less specific as to structural features, it is to be understood that the 45 invention is not limited to the specific details shown, but that the means and construction herein disclosed comprise but one of several modes of putting the invention into effect, and the invention is therefore claimed in any 50 of its forms or modifications within the

legitimate and valid scope of the appended claims.

We claim:

1. A reinforcement for a composition wall comprising substantially parallel flat metallic plates spaced apart and connected by two series of wires lying in spaced planes each substantially parallel to the face of the wall. 55

2. In a reinforcement for composition walls, a metallic plate set substantially at right angles to the face of the wall and having a perforation spaced from its edge, a wire extending through the perforation and a wedge member in the perforation to secure 60 the wire therein. 65

3. In a reinforcement for composition walls, a corner member comprising plates substantially at right angles to the meeting faces of the walls and reinforcements secured to one or more of the plates extending 70 into the space between the plates and the corner of the wall.

4. A reinforcement for composition walls comprising a plurality of substantially parallel flat plates, and a plurality of intermediate reinforcing elements secured end to end substantially in line with each other and extending through perforations in the plates 75 to hold the plates spaced and to provide a 80 reinforcement. 85

5. A reinforcement for composition walls comprising a plurality of plates extending transversely of the wall for substantially the entire thickness of the rough wall, the plates 85 having a series of spaced perforations at a distance from each edge of approximately one-fourth the width of the plate and a plurality of wires extending diagonally between the plate in spaced planes parallel to the 90 edges of the plates, the wires extending through the perforations and being secured therein.

In testimony whereof we affix our signatures in presence of two witnesses.

HENRY KLEIN.
PAUL J. KLEIN.
